UNITED STATES PATENT OFFICE.

RAYMOND C. RUPP, OF KENDALLVILLE, INDIANA.

DOOR CLOSURE FOR THE TOP PORTIONS OF AUTOMOBILES.

1,414,585.

Specification of Letters Patent.

Patented May 2, 1922.

Application filed March 17, 1921. Serial No. 452,914.

To all whom it may concern:

Be it known that I, RAYMOND C. RUPP, a citizen of the United States, residing at Kendallville, in the county of Noble and State of Indiana, have invented certain new and useful Improvements in Door Closures for the Top Portions of Automobiles; and I do declare the following to be a full, clear, and exact description of the invention, such as will enable others skilled in the art to which it appertains to make and use the same.

This invention relates to an improved door for use in connection with the top portion of an automobile body and is primarily intended for use in connection with a removable top used in connection with a touring car and put in place during cold weather and during rainy weather.

One object of the invention is to so construct the curtain or door that it may slide vertically and to further so mount the door that doors upon opposite sides of the body may be moved upwardly to extend across the top with their inner end portions in overlapping relation.

Another object of the invention is to so construct the doors that they may easily move into the overlapping relation without danger of the inner end portions catching and preventing them from overlapping.

Another object of the invention is to so construct the door or curtain that the inner end portion will be curved and thus permitted to easily slide up into the inoperative position.

Another object of the invention is to provide type of frame construction for the door or curtain, the same being so constructed that it will be held in the bent or curved position and the door or curtain securely braced.

Another object of the invention is to so construct this curtain that the metal strip forming the framework will be protected from dampness and thus prevented from rusting.

Another object of the invention is to so construct this curtain that a flap at the lower end portion will provide actuating means for moving the curtain vertically and further provide means for releasably securing the curtain in a raised or lowered position.

Another object of the invention is to so construct the curtain that it may slide in

vertical tracks provided in the body portion of the cover above the body of the touring car.

Another object of the invention is to provide improved means for supporting the curtain when moved up into inoperative position beneath the cover.

Another object of the invention is to so construct the same that it may be applied to a conventional construction of removable top or used in connection with a conventional structure of limousine or sedan body construction.

This invention is illustrated in the accompanying drawings, wherein:

Figure 1 is a view showing an automobile in side elevation with the doors or curtains in the lowered position.

Figure 2 is a vertical transverse sectional view through a portion of the automobile disclosed in Fig. 1 and the curtains in the raised position.

Figure 3 is a horizontal sectional view through the structure of Fig. 2 showing the curtains and supporting frame in plan.

Figure 4 is a perspective view of one of the curtains, portions of the same being broken away.

Figure 5 is a view showing one of the curtains in elevation.

Figure 6 is a transverse sectional view taken along the line 6—6 of Fig. 5.

Figure 7 is a fragmentary view showing in perspective a portion of the upper end portion of one of the curtains.

Figure 8 is a view similar to Fig. 7 showing a portion of the curtain used upon the opposite side of the car and extending in overlapping relation to the curtain of Fig. 7 when in an inoperative position.

This improved curtain is used in connection with the top portion 1 of an automobile 2, the top as previously stated preferably being a removable top fitting upon a touring car. It will be understood however that the device can be used in connection with an automobile of the limousine or sedan type in which the top is an integral portion of the automobile body. This top 1 is provided with the usual door opening which will be positioned above the doors of the automobile body and at the sides of the opening will be provided tracks 3 formed preferably of channel iron and having their upper end portions curved inwardly as shown in Fig. 2

so that the curtains will be guided and caused to pass beyond the inner sides of the side bars 4 which form a part of the top frame and are positioned at the sides of the roof 5.

In order to support the curtains beneath the roof 5 there has been provided between each set of side openings a frame as shown in Figs. 2 and 3. This frame is substantially rectangular in shape and is provided with end bars 6 which extend longitudinally of the vehicle top and have their end portions secured to supporting bars 7 which extend transversely of the vehicle top and have their end portions notched as shown in Fig. 2 thus providing seats 7' in which will fit the side bars 4. Strips 8 which are preferably formed of metal are secured to the end strips 6 and have their end portions curved so that these strips 8 will extend transversely of the body close to the roof 5 with their end portions extending downwardly and terminating in operative relation to the tracks 3. From an inspection of Fig. 2, it will be readily seen that the curtains indicated in general by the numerals 9 and 10 in this figure, may readily pass from the tracks to the position disclosed in this figure. It will be further noted that the curtains may be easily drawn down to a closed or operative position as shown in Fig. 1 and that when in the inoperative position disclosed in Figs. 2 and 3, the end portions will extend in overlapping relation.

The curtains 9 and 10 are practically of a duplicate construction with the exception of a slight difference in the inner end portions as shown in Figs. 7 and 8. Each of the curtains is provided with a structure such as shown in Fig. 4. Referring to Fig. 4, it will be seen that the curtain is provided with a frame having inner and outer side bars 11 and 12, the outer strip 12 being formed of resilient metal such as sheet steel and the inner strip 11 being formed of relatively rigid metal such as galvanized sheet iron. Cross strips 13 connect the ends of the strips 11 and 12, these strips 13 being formed of galvanized sheet iron and riveted to the ends of the strips 11 and 12 at the lower end of the frame and at the upper end being riveted to the strip 12 and having the end portions of the strip 11 wrapped about the cross strips as shown at 14. It will thus be seen that after the cross strips 13 have been connected with the upper ends of the strips 12, these strips may be bent as shown and the end portions of the strips 11 then wrapped about the cross strips 13 so that the strips 11 will provide truss strips which will hold the strips 12 in the bent condition. Cross strips 15 which will preferably be formed of wood but may be formed of any desired material which is substantially rigid, are secured to the inner side strips 11 so that

these strips will be held against transverse movement and thus the frame strengthened and reinforced without the elasticity of the strips 12 being interfered with. It will thus be seen that the upper end portion of the frame may have stretching movement and the side strips 12 may have sufficient resiliency to permit the curtain to be moved upwardly or downwardly around the curve at the sides of the roof 5. In order to protect the metal side strips 11 and 12 from exposure to dampness there has been provided jackets 16 formed of oil cloth or other similar rubber coated fabric. The fabric sheets 17 and 18 which form the covering for the doors or curtains will then be put in place and sewed as shown and protector strips 19 are secured at the side portions of the doors or curtains and extend longitudinally in parallel relation to the strips 12 thus protecting the side portions of the curtains against wear when the curtains are raised or lowered. It should be noted that the sheets 17 and 18 extend beyond the strips 12 and will thus provide a flap 20 having a reinforcing strip 21 of metal positioned therein and secured by a socket fastener 22 for engaging studs at the upper extremities of the doorways formed in the side portions of the top. From an inspection of Fig. 2, it will be seen that the studs at the upper ends of these doorways are carried by the strips 4.

From an inspection of Figs. 7 and 8, it will be seen that the only differences between the two doors or curtains shown in these figures and also shown in Fig. 2, is the fact that the door 9 is provided with a cylindrical rod 25 at the upper edge and that the curtain 10 is not provided with this rod 25 but is provided with a small metal rod 26 which is embedded between the extended edge portions of the sheets 17 and 18. Therefore, the upper edge of the door or curtain 10 will taper and will be reinforced so that the two curtains may easily move into overlapping relation as shown in Fig. 2 when raised.

When this improved construction is assembled, the frame shown in Fig. 3 will be connected with the roof portion of the top 1 and the curtains will be put in place to move vertically in the tracks 3. If it is not desired to have the curtains lowered, they will be moved upwardly to the position of Fig. 2, and as they move upwardly, they will leave the tracks and move into place between the frame and the roof 5. When the curtains are moved downwardly to the lowered position, the tab 20 will be released and used as means for drawing the curtains downwardly. It will thus be seen that there has been provided an improved curtain or sliding door so constructed that it may have easy sliding movement from a vertical position to a horizontal position without being bent out of shape and further that an improved support- 130

ing frame has been provided for supporting the curtain in a horizontal position. It will be further noted that the curtain is so constructed that it will be braced transversely 5 and prevented from being bent out of shape by heavy winds or driving rain.

I claim:

1. A closure of the character described comprising a frame having resilient side 10 strips, cross strips secured to the upper and lower ends of said side strips and formed of substantially rigid material, inner side strips of substantially rigid material secured to the lower cross strip and having their upper end 15 portions connected with the upper cross strip with the resilient side strips bent and the rigid side strips holding the resilient side strips in a bent condition, bracing strips connected with the rigid side strips to brace the 20 same against transverse movement, and an envelope receiving said frame and constituting the body of said closure.

2. The combination with a vehicle body including a top having a roof and side walls 25 having openings therein in opposed relation, of closures for the openings slidably mounted for movement from an operative position to an inoperative position beneath the roof,

the closures when in an inoperative position having their inner end portions extending in 30 overlapping relation, and a cam element carried by the inner end portion of one closure for engaging the second closure and guiding the closures into overlapping relation.

3. The structure of claim 2 having the second closure provided at its inner end with a feathered edge for engaging the cam element 35 of the first closure and assisting movement of the closures into overlapping relation.

4. A closure of the character described including a frame having resilient side strips, cross strips connecting said side strips, and truss means connected with said cross strips with the resilient side strips bent adjacent one end of the frame, and an envelope covering 40 said frame and constituting the body of said closure.

5. The structure of claim 4 having the truss means in the form of strips having their lower ends secured to the lower cross 45 strip and their upper ends connected with the upper cross strip.

In testimony whereof I have hereunto set my hand.

RAYMOND C. RUPP.
